UNITED STATES PATENT OFFICE.

WILLIAM B. H. DOWSE, OF NEWTON, MASSACHUSETTS, ASSIGNOR TO THE CONSOLIDATED FASTENER COMPANY, OF PORTLAND, MAINE.

FASTENER.

SPECIFICATION forming part of Letters Patent No. 650,379, dated May 29, 1900.

Application filed January 31, 1898. Serial No. 668,530. (No model.)

To all whom it may concern:

Be it known that I, WILLIAM B. H. DOWSE, a citizen of the United States, residing at Newton, in the county of Middlesex and State, 5 of Massachusetts, have invented a new and useful Improvement in Fasteners, of which the following is a full specification.

My invention relates to that class of separable fasteners consisting of a stud or male member and a socket or female member; and it consists of an improved stud and socket member, as hereinafter set forth.

Referring to the accompanying drawings, Figure 1 is a plan of my improved stud. Fig. 2 is a side elevation of same. Fig. 3 is a section of my stud member set on any material. Fig. 4 is an elevation of the eyelet used with my stud. Fig. 5 is a sectional view of my stud member held in the dies by which it is 20 riveted to any material. Fig. 6 shows one part of my improved socket or female part, consisting of two pieces, L and M. Fig. 7 shows my improved socket-attaching eyelet N. Fig. 8 is a sectional view, showing parts 25 of the socket member united.

The female part or socket consists of the pieces L and M, which are placed on one side of the fabric to which it is to be attached, and the eyelet N, which is inserted on the under side 30 of the fabric and is upset within the top L, firmly gripping the two parts together. The relation between the interior piece M and the edge p of top L is such that edge p flattens and grips the upper edge of the attaching- 35 eyelet firmly between it and the under side of the flange of the interior piece M. Thus the interior piece is permitted to receive and hold the stud when it is presented.

My stud member consists of a stud A and 40 an eyelet B.

The stud A is formed up from sheet metal into the shape shown, having the dome-shaped head X, contracted neck Y, and flange Z. The eyelet B is also formed from sheet metal 45 and has the barrel V and flange W, the eyelet-tube being open at both ends. The head X of the stud is provided with the slit O, which gives it resiliency, so that it may be snapped into the contracted opening of a 50 socket member.

In setting the stud member on any material

the eyelet B is placed on a properly-shaped die C, as shown, and inserted in the material. The stud A is then placed on the eyelet B, being held in a die D, which has a cavity 55 properly adapted to the shape and size of the head X, and the two parts are pressed together with the result that the barrel V of the eyelet B is upset within the head X of the stud A, so that it cannot be withdrawn 60 through the contracted neck Y. The stud is thus firmly riveted to the material without changing its shape or resiliency.

It will be perceived from the drawings, Fig. 3, that the result of the foregoing operation 65 is that the head of the eyelet is depressed below the roof of the stud and at the same time is expanded to form a locking-head h, with its radial perimeter somewhat angular and bearing against the inner surface of the stud, and 70 its lower portion n contracted so as to stand adjacent to and free from the adjacently-surrounding metal of the neck of the stud. This construction creates a more yielding connection between the united parts than in 75 instances where the head and neck of the attaching-eyelet fills the neck and dome of the stud.

I purposely make the cavity of my stud-die D a little less than the height of my stud, so that 80 in the operation of setting the dome X of the stud is pressed down slightly to meet the eyelet and at the same time firmly supported by the die. When the die is removed, the dome springs back by virtue of its resiliency, leaving 85 a space P above the riveted end of the eyelet, as shown in Fig. 3.

I am aware that resilient studs have been made before, but they have always been made when the attaching-eyelet upsets within the 90 stud, with an anvil or dome inside, whereby and wherein the riveting-eyelet is clenched. I have discovered that by using a stud of substantially the form shown in the accompanying drawings and by making the setting-die 95 properly adapted to the stud, the stud can be properly riveted without using any inside anvil or retaining-piece and without destroying either its form or its resiliency.

I am well aware that solid or non-resilient 100 studs have been attached in this general manner; but I believe that resilient studs, when

the attaching-eyelet is upset within the stud, have never before been riveted without some inside anvil or dome.

I claim—

- 5 In a separable fastener, the combination with a socket member, of a stud member comprising a dome-shaped head having a transverse slit and formed with a base-flange, and a contracted neck immediately above the
10 flange and an eyelet having a base-flange and a vertical tube open throughout its length being primarily of less diametrical extent than the entrance to the dome-shaped head, and upset within said head and above the

minimum contraction of the entrance to the head to form a locking-head h with its radial perimeter angular and bearing against the inner face of the cap and its lower portion n contracted and free from the surrounding metal of the neck of the cap, substantially as 20 and for the purpose specified.

In witness whereof I have hereunto set my hand and seal.

WM. B. H. DOWSE. [L.S.]
